SEWING MACHINE

George A. Fleckenstein, Stratford, Conn., assignor to The Singer Manufacturing Company, Elizabeth, N. J., a corporation of New Jersey

Application September 28, 1939, Serial No. 296,871

4 Claims. (Cl. 112—220)

This invention relates to sewing machines, more particularly of the small, portable, electrically driven type for family use.

Machines of this type are commonly constructed with a flat box bed and overhanging bracket-arm; the main-shaft and its driving motor being located in the box bed.

A modern lock-stitch family sewing machine requires a bobbin-thread and loop-taker mechanism which will run smoothly, quietly and efficiently without annoying vibration. It is also a desideratum that the bobbin be readily accessible for replenishment. These requirements are fulfilled by a loop-taker of the vertical axis two-to-one rotary hook type, such as used in the present machine embodying the invention.

The invention has for an object to provide a portable electric lock-stitch family sewing machine of simple construction, the elemental mechanisms of which are of proven types and are so arranged and related as to require but few parts for their actuation.

The invention has for a further object the provision of a simplified gearing and shaft arrangement for a box bed family machine driven by a small high speed motor disposed in said bed, the machine having a balance-wheel which is belt-driven by said motor and is small enough to clear the table on which the machine may be stationed for use.

The invention is concerned with attaining the above objects while interconnecting various machine shafts in the box bed for rotation at the proper relative speeds for actuation of the several elemental mechanisms of the machine, namely, the needle-bar mechanism, the rotary-hook mechanism and the work-feeding mechanism.

In the accompanying drawings, Fig. 1 is a longitudinal vertical section through a sewing machine embodying the invention. Fig. 2 is a bottom plan view of the machine. Fig. 3 is a transverse vertical section through the machine bed on the line 3—3, Fig. 2, with the bracket-arm head in elevation. Fig. 4 is a section on the line 4—4, Fig. 2, and Fig. 5 is a vertical section transversely of the machine bed at the bracket-arm standard.

The machine is constructed with a flat box-type bed having the top wall 1, front wall 2, rear wall 3 and end walls 4 and 5. The open bottom of the bed casting is closed by the removable baseboard 6 on which is seated the electric motor 7 having the power-shaft 8 and driving pulley 9.

Rising from the bed 1 is the standard 10 of the overhanging bracket-arm 11 terminating in the

head 12 for the usual needle-bar 13 and spring-pressed presser-bar 14.

Journalized in the bed 1, in the internal boss 15 on the end wall 4 and in the internal bearing bracket 16, is the main-shaft 17 the outboard projection of which carries the hand-wheel and pulley member 18 which is connected by the belt 19 to the motor pulley 9.

Journalized in the bracket-arm 11 is the top rotary shaft 20 which, as usual, drives the needle-bar 13 and take-up 21. The top shaft 20 is geared one-to-one to the vertical shaft 22 which, in turn, is geared one-to-two to the main-shaft 17, so that the main-shaft 17 makes two complete rotations to one rotation of the top shaft 20 which effects one complete reciprocation of the needle-bar 13 or one stitch-forming cycle.

Mounted on the inner end of the main-shaft 17 is a spur-gear 23 which meshes with the spur-gear 24 on the countershaft 25 journalized vertically below and parallel to the main-shaft 17 in the bearing bracket 16 and transverse internal bed-partition 26. The gear 24 is of the same pitch-diameter as the gear 23 but has double the face width, as shown in Fig. 1, so that the countershaft 25 runs at the same speed as the main-shaft 17.

The countershaft 25 is connected by the one-to-one spiral bevel-gears 27 to the vertical hook-shaft 28 which is journaled in the bushing 29 in the bed-bracket 30 and carries the usual rotary loop-taking hook 31 in which the usual stationary bobbin-thread case and bobbin (not shown) are located. Thus, the rotary hook 31 is driven two revolutions per stitch-forming cycle, as is usual with loop-takers of this type.

Journalized at the side of the plane of the axes of the shafts 17 and 25 is the feed-shaft 32 which carries the usual feed-lift eccentric 33 and feed-advance eccentric 34. The feed-lift eccentric 33 lifts the feed-bar 35 which carries the feed-dog 36 and is slidingly fulcrumed on the stationary feed-fulcrum pin 37. The feed-advance eccentric 34 is engaged by the curved lever 38 which is fulcrumed at 39 on the transverse partition wall 26 and is engaged by the push-bar 40 fulcrumed at 41 on the feed-bar 35. A feed-regulating lever 42 is fulcrumed at 43 on the partition wall 26 and, at one end, carries a pin 44 which enters a slot 45 in the push-bar 40. The other end of the feed-regulating lever 42 projects through the slot 46 in the front wall 2 of the bed and is accessible to the operator. The inner end of the lever 42 is slightly sprung or bent to drag upon the face of the partition wall 26 sufficiently to

frictionally retain the lever 42 in any desired set position. The spring 47 in the feed-bar 35 urges the latter in a direction to retain the push-bar 48 in engagement with the curved lever 38 which is thus maintained in engagement with the feed-eccentric 34. The present feeding mechanism, per se, is essentially the same as that disclosed in U. S. Patent No. 1,916,860, dated July 4, 1933. The feed-shaft 32 in the present machine carries a spur-gear 48 which meshes with the gear 24 on the countershaft 25 and is double the pitch-diameter of the gear 24 so that the feed-shaft will make one revolution per stitch-forming cycle. The gears 48 and 23, both of which mesh with the wide faced gear 24 are laterally offset from one another so that they will not conflict.

There is thus attained a simple and unique arrangement of shafts and gearing for driving the essential and proven mechanisms of a vertical-axis rotary-hook sewing machine from a main-shaft journaled in the box-type bed of the machine which contains the high speed electric motor for driving the main-shaft at the proper speed, using a balance-wheel of the moderate size necessary to clear the machine-supporting table.

The bracket-arm 11 and top-shaft 20 are set vertically over the main-shaft 17 which is set forwardly of the longitudinal center line of the bed. The motor 7 is set rearwardly of the main-shaft 17 sufficiently to permit the use of a belt 19 of adequate length for effective driving engagement with the belt-pulleys 9 and 18. The feed-shaft 32 is disposed in the proper relation to the feed-bar 35 to actuate the latter from the feed-eccentrics 33 and 34 and permit of regulation of the stitch-length.

Having thus set forth the nature of the invention, what I claim herein is:

1. A small portable sewing machine of the family type having a hollow box bed and overhanging bracket-arm, an electric motor mounted in said bed, a main-shaft journaled in said bed and driven by said motor at twice stitching speed, a reciprocating needle carried by said bracket-arm and driven at stitching speed by said main-shaft, a vertical axis rotary hook disposed in said bed with its axis in a vertical plane containing the axis of said main-shaft, a countershaft in said plane below and parallel to the axis of the main-shaft and bevel-geared at one end to the vertical hook-shaft, a spur-gear on said main-shaft, a spur-gear on said countershaft meshing with the spur-gear on the main-shaft and having double the face width of the last mentioned spur-gear, feeding mechanism including a feed-shaft journaled at one side of said vertical plane, a large

spur-gear on said feed-shaft laterally offset from the spur-gear on the main-shaft and meshing with the spur gear on the countershaft which drives said rotary hook, so that the feed-shaft is driven at stitching speed by the hook-driving countershaft.

2. In a sewing machine, a frame including a hollow box bed and overhanging bracket-arm, a main-shaft journaled high in said bed, a hand-wheel and belt-pulley on said main-shaft externally of said bed, a reciprocating needle carried by said bracket-arm and driven by said main-shaft, a vertical axis rotary hook-shaft journaled in said bed, a hook-driving countershaft journaled low in said bed and geared at one end to the vertical hook-shaft, intermeshing one-to-one spur-gears on the main-shaft and countershaft, respectively, work-feeding mechanism including a feed-shaft, and a spur-gear on the feed-shaft of twice the pitch-diameter of the spur-gear on the hook-driving countershaft and meshing with said last mentioned spur-gear.

3. In a sewing machine, a frame including a flat box bed and overhanging bracket-arm, a main-shaft journaled horizontally and high in said bed in front of a longitudinal central vertical plane cutting said bed, a reciprocating needle carried by said bracket-arm and driven by said main-shaft, a vertical-axis rotary-hook shaft journaled in said bed in front of said vertical plane, a hook-driving countershaft journaled horizontally and low in said bed and geared to the vertical hook-driving shaft, a spur-gear on the main-shaft, a spur-gear on the hook-driving countershaft in mesh with the spur-gear on the main-shaft, a work-feeding mechanism including a feed-shaft disposed horizontally at an elevation intermediate the levels of the main-shaft and hook-driving countershaft and in rear of said last two mentioned shafts, and a large gear on the feed-shaft meshing with the gear on said hook-driving countershaft.

4. A sewing machine having a flat hollow box bed constructed with a transverse internal partition wall and an internal bearing bracket spaced from said partition wall, a rotary hook driving countershaft and a feed-shaft journaled in parallelism in said partition wall and bearing bracket and geared together so that the feed-shaft will make one revolution to two revolutions of the hook-driving countershaft, a main-shaft journaled in said bearing bracket and one of the end walls of said bed, and a gear on said main-shaft meshing one-to-one with the gear on the hook-driving countershaft.

GEORGE A. FLECKENSTEIN.
